SPICE RACK

Walter Clifford Pierce, Jr., Inglewood, Calif.

Application December 11, 1953, Serial No. 28,026

Term of patent 7 years

(Cl. D44—6)

Fig. 1

Fig. 1 is a front isometric view of a spice rack showing my new design;

Fig. 2 is a side elevational view thereof; and

Fig. 3 is a top plan view thereof.

I claim:

The ornamental design for a spice rack, as shown.
